CLAIM

The ornamental design for an “illuminated marshalling wand”, as shown and described.

DESCRIPTION

FIG. 1 is a bottom, front, and left side perspective view showing my new design for an illuminated marshalling wand.

FIG. 2 is a front view of the illuminated marshalling wand shown in FIG. 1.

FIG. 3 is a rear view of the illuminated marshalling wand shown in FIG. 1.

FIG. 4 is a top view of the illuminated marshalling wand shown in FIG. 1.

FIG. 5 is a bottom view of the illuminated marshalling wand shown in FIG. 1.

FIG. 6 is a left side view of the illuminated marshalling wand shown in FIG. 1.

FIG. 7 is a right side view of the illuminated marshalling wand shown in FIG. 1; and,

FIG. 8 is a bottom, front, and left side perspective view of the illuminated marshalling wand shown in FIG. 1.

The broken lines show portions of the illuminated marshalling wand which form no part of the claimed design. The carabiner tether in FIG. 8 is shown only for environmental purposes.
